UNITED STATES PATENT OFFICE.

HOWARD C. CLEAVER, OF LONDON, ENGLAND.

INTERNAL-COMBUSTION ENGINE.

1,172,940.

Specification of Letters Patent. Patented Feb. 22, 1916.

Application filed October 23, 1909. Serial No. 524,263.

To all whom it may concern:

Be it known that I, HOWARD CRUNDEN CLEAVER, a subject of the King of Great Britain, residing at 35 Berners street, in the county of London, England, engineer, have invented new and useful Improvements in Internal-Combustion Engines, of which the following is a specification.

This invention relates to improvements in internal combustion engines with single acting cylinders of the class in which a rotating cylindrical valve with its outer surface in contact with the inner surface of the cylinder, is provided with a port adapted to register successively during the rotation of said valve with an exhaust port and an induction port cut in the walls of the cylinder.

Internal combustion engines of this class have been suggested provided with a cylindrical rotating valve situated inside the closed end of the cylinder which valve was either in the form of a single rotating cylinder or in the form of an inner and outer cylinder respectively adapted to rotate in opposite directions. The said cylindrical valves were provided with extended walls forming the inner lining of the cylinder and were provided with a toothed rim or rims at the extremity of said extended walls adapted to engage gearing rotated by the main shaft of the engine.

According to the present invention I provide a cylinder having a closed and an open end with the ports for induction and exhaust and a reciprocating piston operating therein. On the outer surface of the said cylinder I provide a cylindrical rotating valve which may be in the form of a single rotating cylinder or in the form of an inner and an outer cylinder respectively adapted to rotate in opposite directions.

By the arrangement of the cylinder between the piston and the valve I am enabled to avoid the friction that would be caused by the reciprocating movement of the piston directly within the valve while it was itself rotating. Further, by my arrangement the extended walls of said valve may be perforated, grooved or cut away to any convenient extent so that a great deal of friction can be avoided and lubrication assisted without interfering with the perfect sealing of the ports.

My invention is illustrated by way of example in the accompanying drawings in which I show the rotating valve between the

cylinder and an outer cylindrical valve casing which is in the form of a water jacket apertured for the passage of gases. It will be understood that this outer valve casing is not an essential or an integral portion of the engine of my invention and can, if desired, be dispensed with.

In the accompanying drawings, Figure 1 shows a sectional side view of one unit of my internal combustion engine with a rotary cylindrical valve. Fig. 2 shows a front elevation partly in section of a four cylinder internal combustion engine built up from units such as are shown in Fig. 1. Fig. 3 shows a plan view partly in section of Fig. 2. Fig. 4 is a detail view of the valve 2. Fig. 5 shows a sectional side view of another alternative construction of my internal combustion engine with a valve formed of inner and outer cylinders adapted to rotate in opposite directions, and Fig. 6 shows a section on the line C—D of Fig. 5.

Referring now to Figs. 1, 2 and 3 of the drawings, I provide a cylinder 11 on the outer surface of which is arranged a rotating cylindrical valve 2. The port 3 of said valve is adapted to register successively during its rotation, with the exhaust port 4 and the induction port 5, shown more particularly in Fig. 3, in the upper part of said cylinder 11. The reciprocating piston 10 moves in said cylinder 11.

As shown in Fig. 1, in which an engine provided with an outer valve casing 1 is illustrated, the said rotary cylindrical valve 2 is elongated and extended beyond the open end of the cylinder 11 there terminating in the form of a milled or toothed rim 6, the said toothed rim 6 being engaged by a bevel gear wheel 7, as shown, or helical gearing or the like, to which the rotary movement is communicated through gearing 8 from the shaft 9 of the engine, thus causing the said cylindrical valve 2 to rotate on the outer surface of the cylinder 11. Instead of the above described toothed rim it will be obvious that when the valve casing 1 is dispensed with a toothed flange may be arranged upon any exposed portion of the valve cylinder, provided that motion can be communicated thereto from the shaft of the engine. The head of the said valve casing 1 is immovably secured to the cylinder head 14, which is pierced at any convenient point or points to receive a sparking plug 13 or plugs for the purpose of ignition.

The force of the explosion and compression when exerted within the cylinder during the operation of the engine is partly directed and received upon those portions of 5 the rotating cylindrical valve which, for the time being, close the ports 4 and 5. Owing to the fact that these ports 4 and 5 are situated within an arc of about 45° , the greater pressure is exerted upon the imperforate 10 side of said rotating cylindrical valve, thereby causing an increase of friction between said valve and cylinder and somewhat impeding the ease of its rotation. To obviate this fault (when a valve casing is 15 used) I may perforate the walls of the cylinder opposite to the two ports of said cylinder. This third perforation admits the explosive force to impinge upon that part of the wall of the rotating cylindrical valve 20 opposite to the said ports, thereby giving poise and counterbalance to the rotary valve at all times during the complete cycle of operations.

As will be readily understood from Figs. 25 1, 2 and 3 of the drawings the above described combination of a rotary cylindrical valve, a cylinder and a reciprocating piston actuating the crank shaft or the like forms one element or unit of the engine.

30 In Fig. 4 I have shown a cylindrical valve 2 having suitable grooves in the surfaces thereof, said grooves being arranged at an angle with respect to the vertical axis of the valve. It will be seen that by this 35 structure the external surface of the valve casing 1 is greatly reduced and consequently friction between the valve and valve casing is reduced.

In Figs. 5 and 6 I show an alternative 40 construction of the internal combustion engine of my invention. The rotating valve, as shown in the drawings, is here formed of an inner and an outer valve-member 28 and 27 respectively, adapted to be rotated in opposite directions by means of suitable gearing. If a valve casing is used the walls of 45 said valve-members 28 and 27 may be extended, as shown, and may be provided with milled rings 30 and 29 respectively at their 50 extremities which are engaged by the bevel wheels 32 and 37 rotated from the main shaft of the engine. The said outer valve-member 27 is provided with a single port 32, while the inner valve-member 28 is provided with two ports 33 and 34, (see Fig. 6). It will be obvious that the said two 55 ports 33 and 34 will register alternately with the said port 32 of the rotating valve-member 27 and that this registration will 60 alternately be effective and ineffective. It will be effective when the port of the said rotating valve-member is in registration with either the exhaust port or the induction port of the piston cylinder. By the arrangement of the said pair of valve-mem-

bers rotating in opposite directions I obtain an enlargement of the ports and effect a more rapid opening and closing of said ports.

In operation—at the moment when the 70 port in the inner valve-member is registering with the inlet port of the cylinder the piston is descending and creating a suction. The charge is then compressed by the return stroke of the piston, and is ignited after 75 completion of the compression stroke. At the moment of ignition the shaft has accomplished one complete and one half revolutions and the valve members have been rotated through 270° while both ports in the 80 cylinder have been closed during the compression and ignition. On the continued rotation of the shaft the exhaust port is opened and the gases escape during the second return stroke of the piston, thus completing 85 a cycle of four strokes of the piston for every revolution of the valve members.

What I claim is:

1. In an internal combustion engine, the combination of a plurality of cylinders, 90 each of the cylinders having opposite induction and exhaust ports in adjacent pairs of said cylinders, pistons reciprocating in said cylinders, a crank shaft rotated by said pistons, a plurality of cylindrical valves with 95 extended grooved walls adapted to rotate within said cylinders, means for rotating one of said cylindrical valves from said crank shaft, toothed flanges on each of said cylindrical valves, said toothed flanges 100 adapted to communicate a rotary motion from the valve rotated from the crank shaft to the valves of the other engine units.

2. In an internal combustion engine, the combination of an inner and outer cylinder 105 having induction and exhaust ports, of rotary cylindrical valves supported between the cylinders, a piston operating in the inner cylinder so that the walls of the piston will engage the inner walls of the inner cylinder, one of said valves having grooves in the outer surface thereof, said grooves being disposed at an angle with respect to the vertical plane of the piston.

3. An engine cylinder comprising an 115 outer cylinder and an inner cylinder, the inner cylinder being supported in spaced relation with the outer cylinder to form an annular recess between the cylinders, each of the cylinders having intake and exhaust 120 ports arranged at right angles to each other, a piston operating in the inner cylinder, and means adapted to rotate in the annular recess, said means adapted to alternately open and close the intake and exhaust ports of 125 the cylinder.

4. In an internal combustion engine, the combination of a plurality of cylinders, each of the cylinders having opposite induction and exhaust ports in adjacent pairs of said 130

cylinders, pistons reciprocating in said cylinders, a crank shaft rotated by said pistons, a plurality of cylindrical valves with extended walls adapted to rotate without 5 said cylinders, means for rotating said cylindrical valves from said crank shaft.

5. In an internal combustion engine, the combination of a cylinder having induction and exhaust ports of a rotary cylindrical 10 valve supported without the cylinder, a piston operating in the cylinder so that the walls of the piston will not engage the inner walls of the valve, said valve having grooves in the surface thereof, said grooves 15 being disposed at an angle with respect to the vertical plane of the piston.

6. An engine cylinder comprising an outer cylinder and an inner cylinder, the inner cylinder being supported in spaced relation 20 with the outer cylinder to form an annular recess between the cylinders, each of the cylinders having intake and exhaust ports arranged in pairs, a piston operating in the inner cylinder, a ported cylindrical 25 valve in the annular recess, and means adapted to alternately open and close the intake and exhaust ports of the cylinder by rotation of the said ported cylindrical valve.

7. In an internal combustion engine, the 30 combination with a cylinder comprising an external casing and internal casing spaced apart, of an orificed cylindrical valve shell inserted between the two casings of the cylinder, the internal casing having supply and 35 exhaust openings registering respectively with the supply and exhaust openings in the external casing, a reciprocable piston within the internal casing, the crank-shaft,

and connections between the crank-shaft and valve shell adapted to turn the same to 40 successively connect the piston chamber with the supply and exhaust openings and seal it from both openings.

8. In an internal combustion engine, the combination with a cylinder having an external casing and an internal casing spaced apart and each provided with supply and exhaust openings, of a rotatable cylindrical valve shell between said casings and adapted to open and close said openings and to 50 connect the openings in the external casing with the openings in the internal casing, a piston within the internal casing, and connections between the crank shaft and the piston and valve adapted to operate the 55 same.

9. In an internal combustion engine, the combination with a cylinder casing having orifices communicating with the supply and exhaust, of a rotatable orificed valve shell 60 within said casing and an orificed casing within the valve, connections between the crank-shaft and valve shell adapted to rotate the same, a piston within the last-named casing and connections between the crank 65 shaft and piston, to actuate the latter, said valve in its rotation to open communication from the interior of the cylinder to the supply and exhaust through said orifices.

In testimony whereof I have signed my 70 name to this specification in the presence of two subscribing witnesses.

HOWARD C. CLEAVER.
